UNITED STATES PATENT OFFICE.

LOUIS SNYDER, OF PHILADELPHIA, PENNSYLVANIA.

PADLOCK.

1,367,104.

Specification of Letters Patent.

Patented Feb. 1, 1921.

Application filed May 28, 1920. Serial No. 384,823.

To all whom it may concern:

Be it known that I, LOUIS SNYDER, citizen of the United States, residing at Philadelphia, in the county of Philadelphia and State of Pennsylvania, have invented a new and useful Improvement in Padlocks, of which the following is a specification.

This invention relates to padlocks of the class shown in Patent No. 1,209,894, granted 10 to me December 26, 1916. In such padlocks the hasps are unlocked and allowed to spring open by the mere inward thrust of a key having the proper outline.

The object of the invention is to simplify 15 and cheapen the manufacture and assembly, and at the same time render more secure, padlocks of the class shown in my prior patent.

In the accompanying drawings Figure 1 20 shows a side view of a padlock that embodies the invention. Fig. 2 shows an edge view of the same. Fig. 3 is a section through the casing showing the parts in locked position and the key before it is inserted. Fig. 4 is a similar section with the parts in 25 unlocked position. Fig. 5 shows a side view of the locking mechanism removed from the casing. Fig. 6 shows a top view of the locking mechanism. Fig. 7 shows an end 30 view of the locking mechanism.

The casing 1 of the padlock is cast to the desired shape in a single piece of any suitable metal, as iron, brass or bronze, with hasp openings 2 and 3 in one end and a key 35 hole 4 of suitable outline in one side near the other end. In making the casing the chamber and the hasp openings are produced by cores placed in the mold and it is desirable to insert the key 5 in the mold and cast 40 the metal about it so as to form a key hole which conforms to the shape of the key to be used with the particular lock, thus obviating the necessity of performing any machining operations on the casing.

The hasp 6 which can be cast to shape is 45 pivotally held in the opening 2 by a pin 7 which is driven through and headed on both ends flush with the sides of the casing, and the swinging end of the hasp is adapted to 50 be turned into and out of the opening 3. The end of the hasp in the interior of the casing curves downward from the pivot pin toward the bottom of the chamber and is provided with an angular notch 8. A spring 55 9 which is coiled about a stud 10 cast on the side of the hasp and is arranged to press

against the side wall of the casing, tends to throw the hasp open.

The locking member comprises a bolt 11 which is pivoted to a block 12 and has its 60 free end thrown up by a spring 13 into the notch formed in the inner end of the hasp, this spring being coiled about a stud 14 cast on the side of the block to which the bolt is pivoted. The bolt has a downwardly extending foot 15, the upper face of which is desirably formed on an angle of approximately thirty degrees to the end of the foot. Secured to one side of the block near the pivot end is a leaf spring 16, and on the free 70 end of this spring is a guard plate 17 which is adapted to be held by the spring with its edge extending into a notch 18 on the block in front of the free end of the locking bolt. Projecting forwardly from the guard plate 75 is a thin pointed finger 19. In front of the guard plate the side face of the block is cut out to conform to the outline of the key and along the top of the block in front of the guard plate is a protecting rib 20. The 80 block which supports these locking and protecting parts is approximately as long as the width of the opening in the interior of the casing.

In assembling the structure the block 85 bearing the locking bolt, guard plate and lifting finger is dropped into the casing through the opening 2 before the hasp is inserted. Then the end of the block near the key opening is secured in place by 90 means of a screw 20 (shown in dotted lines in Fig. 5) that after it is screwed in from the outside of the casing is cut off flush with the face of the casing. The other end of the block which carries the locking parts merely 95 butts against the edge wall above the bottom of the casing. After the locking parts have been fastened in place the hasp is located in position and the pivot pin driven through and headed flush with the casing. 100 When the hasp is turned down to locking position its inner end is engaged by the free end of the locking bolt which is thrown by its spring up into the notch in the end of the hasp. With the parts in this position 105 the hasp cannot be opened, for any tendency to swing it open is resisted by the locking bolt which extends between the inner end of the hasp and the side wall of the casing lengthwise in the path of movement of 110 the end of the hasp. To open the lock a key having the proper grooves milled in its side

to fit the key slot in the edge of the casing and the grooves in the end of the lock holding block and provided with an angular front end is thrust into the keyhole. The 5 first action of the key is to engage the finger and to raise the guard plate out of the path of the end of the key. As the inward movement of the key continues its inclined end engages the inclined upper face of the foot 10 that projects from the locking bolt and draws the free end of the locking bolt downward out of engagement with the notched end of the hasp, which when freed is thrown open by its spring. As the hasp is thrown 15 open and the key removed the free end of the locking bolt is thrown up against the lower end and holds the hasp open until it is swung to closing position and the locking bolt again engaged with the notched inner end. Only a key of the proper outline 20 can be inserted into this padlock, and the guard plate cannot be lifted from in front of the shoe on the end of the locking bolt except by the insertion of the proper key. 25 A small wire or pin will not engage the finger so as to lift the guard plate and nothing can pass the guard plate until it is lifted. This padlock requires practically no machining operations in its manufacture, 30 the parts being mostly cast to final shape. It is easy to assemble, and when assembled and finished it is practically impossible to see how it was put together, for the casing, 35 is in one piece and there is apparently no opening, after the hasp is in place, for the locking parts to be inserted, and no way is known of picking it. Maximum strength is insured as a result of the construction, and particularly for the reason that any attempt 40 to swing the hasp open is resisted by the thrust of the inner end of the hasp in a direct line of the entire length of the locking bolt which is backed up by the side wall of the casing. 45 The invention claimed is:—

1. A padlock having a casing provided with a keyhole in its edge and two hasp openings in its end, a hasp pivotally held in one of said openings and adapted to be swung into and out of the other of said openings, a spring tending to throw the hasp open, a block dropped into the bottom of the casing and extending from side to side, a locking bolt pivotally attached to one end of said block, a spring adapted to throw the free end of the bolt up into engagement with the inner end of the hasp, a foot extending from the free end of the locking bolt into line with the key opening, a guard plate normally

held by a spring between said foot and key 60 opening, and a finger projecting from the guard plate toward the key opening.

2. A padlock comprising a casing having a keyhole in one side and two hasp openings in its end, a hasp pivotally held in one of 65 said openings and adapted to be swung into and out of the other of said openings, the inner end of said hasp having a locking notch and bearing a spring adapted to engage the side wall of the casing and throw the hasp open, a block located in the bottom of the casing, said block carrying a locking bolt, a spring adapted to thrust the end of the locking bolt into engagement with the notch in the inner end of the hasp, 70 a foot projecting from the locking bolt into line with the key hole, a spring-pressed guard plate normally extending between said foot and the key hole, a finger projecting from the guard plate toward the key 75 hole, and a protecting rib extending from the edge of said block parallel with the key path.

3. A padlock comprising a casing with a key hole in one side and two hasp openings 85 in one end, a hasp pivotally held in one of said openings and having its outer end adapted to swing into and out of the other openings, a spring adapted to throw the hasp open, a locking bolt normally extending lengthwise between the inner end of the hasp and the side wall of the casing, a pivot for loosely retaining one end of the locking bolt, a spring for thrusting the other end of the locking bolt into engagement with the inner end of the hasp, a foot with an angular upper face extending from the free end of the locking bolt into line with the key 90 opening, and means normally extending in front of said foot and adapted to be raised 100 by the insertion of a key before the key can engage said foot for drawing the bolt down out of engagement with the inner end of the hasp.

4. A padlock having a casing with two 105 hasp holes in one end and a key hole in one side, a hasp pivotally held in one opening and adapted to swing into and out of the other opening, said hasp having a locking notch in the interior of the casing, a block 110 located in the bottom of the casing, a bolt pivotally attached to the block and extending between the side wall of the casing and notch in the hasp, and means for withdrawing the end of the bolt from the notch in 115 the hasp.

LOUIS SNYDER.
